UNITED STATES PATENT OFFICE.

ROBERT J. BARTHOLOMEW, OF LANSDALE, PENNSYLVANIA, ASSIGNEE TO FLETCHER WORKS, INCORPORATED, OF PHILADELPHIA, PENNSYLVANIA, A CORPORATION OF PENNSYLVANIA.

HARNESS FRAME FOR LOOMS.

Application filed October 11, 1926. Serial No. 140,758.

My invention relates to an improvement in looms, and relates specifically to an improvement in harness frames thereof.

In looms as now constructed, the frames which are suspended in parallel planes are arranged side by side and in contact with each other. Inasmuch as the frames have movement vertically relatively to each other, depending upon the material being woven, the friction between the frames places a considerable load on the jacks or other lifting device for the frame, depending upon the type of loom under consideration, and it is an object of the present invention to reduce this load to such an extent that the strain on the lifting device or devices will be reduced to a minimum, thereby enabling light type looms to weave heavier fabrics than now possible and with no more strain on the mechanism. To accomplish this object, I interpose anti-friction devices between adjacent harness frames, thereby reducing the friction between the harness frames to such an extent that the load on the harness motion is reduced to a minimum in lifting the frames while relatively small weights or springs may be employed for lowering the frames.

In the accompanying drawings, wherein I have illustrated an embodiment of my invention,—

Fig. 1 shows in elevation a set of harness frames with my improvement applied thereto;

Fig. 2 is an end elevation of the frames; and

Fig. 3 is an enlarged view of one of the frames with part of the same broken away to show details of construction.

Referring to the drawings in detail, 1, 2 and 3 designate three harness frames adapted to be raised by the jacks 4, 5 and 6, respectively, of a harness motion and to be pulled down by weights 7, 8, 9 and 10. I have not attempted to show in detail the construction or operation of the jacks 4, 5 and 6, inasmuch as this constitutes no part of my invention. I might mention, however, that the jack 4 is attached to the frame 1 by the usual flexible connection 11, the jack 5 to the frame 2 by a similar connection 12, and the jack 6 to the frame 1 by a similar connection 13. These connections run over pulleys 14. The operation of the jacks 4, 5 and 6 will, as will be apparent, raise the

frames, while the lowering of the frames is accomplished by weights 7, 8, 9 and 10, or springs, or other suitable means, as desired.

As I have above pointed out, in looms as now constructed, the frames 1, 2 and 3 which in actual practice are in parallel relation, are in contact with each other, so that as the frames are raised and lowered relatively to each other, one frame slides over the other and in contact with it. This creates considerable friction and hence a load on the harness motion, and to prevent contacting of the frames and at the same time reduce the friction between the frames, I secure to each end of the frame 1 one or more roller brackets 15. Two have been illustrated. These brackets are set into the frame and held in place by screws 16 or other suitable means. Each bracket carries a roller 17, the periphery of which projects a short distance beyond the face of the frame adjacent the face of the frame 2, as indicated at 18. These rollers are preferably oil-impregnated, inasmuch as it is desired to eliminate friction as much as possible and owing to the location of these rollers in proximity to the warp, it will be obvious that the oiling of the rollers after once installed would be very difficult and objectionable.

The frame 2 is provided with two or more rollers 19 similar to the rollers 17 and carried by brackets secured to the frame, the same as described in connection with the frame 1. The peripheries of the rollers 19 project a short distance beyond the face of the frame 2 adjacent the frame 3 as indicated at 20.

The frame 3 will likewise be provided with two or more rollers 21 projecting beyond the face thereof if frames additional to frames 1, 2 and 3 are to be employed, as will be understood.

It will be apparent from the foregoing that in the raising and lowering of the frames, effected by the jacks 4, 5 and 6 and weights 7, 8, 9 and 10, the frames will be maintained out of contact with each other and be caused to move on the rollers 17 and 19, and if additional frames are employed on the rollers 21 as well, so that the friction between the frames is reduced to a minimum. This will relieve to a great extent the load on the jacks 4, 5 and 6 or other lifting device employed and enables the size of the

weights 7, 8, 9 and 10 or the size of the springs being employed to be reduced to the minimum in pulling the frames downwardly. This arrangement, as above pointed out, also 5 enables light type looms to weave heavier fabrics than now possible and with no more strain on the mechanism.

While I have described an embodiment of my invention and have shown the rollers attached to the frames by mounting the same in brackets held to the frames by screws, the rollers themselves lying in recesses 22 provided for that purpose in the frames, it will be understood that other means may be devised 10 for mounting the rollers within the purview of my invention.

I wish it to be understood, also, that the number and location of the rollers with respect to the frames may be varied within 15 my invention.

What I claim is:

1. In combination, a plurality of frames arranged in parallel relation and having movement relatively to each other, and anti-friction rollers carried by the frames and with which the frames contact in their 20 movements.

2. In combination, a plurality of juxtaposed harness frames arranged in parallel

relation to each other, and an anti-friction 30 roller secured to one frame and having its periphery projecting from the face thereof and engaged by the adjacent frame.

3. In combination, a plurality of harness frames, the face of one frame adjacent the 35 adjoining frame being provided with a depression, a bracket secured to said frame, an anti-friction roller mounted in said bracket and lying in said depression, the periphery of said roller extending or projecting beyond the face of said frame to prevent contact of the frames with each other.

4. In combination, a plurality of harness frames, a plurality of brackets set into one of said frames, an oil-impregnated roller 40 rotatably mounted in said bracket, the periphery of said roller extending beyond the plane of the face of the frame to contact with one face of the adjacent frame.

5. In a loom, the combination of a plurality of rectangular harness frames lying side by side in parallel relation to each other, and anti-friction rollers attached to the ends of said frames and interposed between the 45 faces of adjacent frames.

This specification signed this 7th day of October, 1926.

ROBERT J. BARTHOLOMEW.
